UNITED STATES PATENT OFFICE

153,074

DESIGN FOR A PAIR OF SHEARS

Arne Oker, Southbridge, Mass., assignor to Hyde
Manufacturing Company, Southbridge, Mass.,
a corporation of Massachusetts

Application December 5, 1946, Serial No. 135,269

Term of patent 14 years

(Cl. D22—5)

To all whom it may concern:

Be it known that Arne Oker, a citizen of the United States, residing at 72 Hillside Road, Southbridge, in the county of Worcester and State of Massachusetts, have invented a new, original, and ornamental Design for Pair of Shears, of which the following is a specification, reference being had to the accompanying drawing, forming part thereof.

Fig. 1 is a view in front elevation; and

Fig. 2 is a view in rear elevation of a pair of shears showing my new design, and

Fig. 3 is an edge view thereof.

I claim:

The ornamental design for a pair of shears, as shown.

ARNE OKER.
